UNITED STATES PATENT OFFICE.

LESLIE HALWORTH CLARK, OF AUCKLAND, NEW ZEALAND, ASSIGNOR TO HAROLD
LESLIE BELL AND JOHN RICHARD HERDEN, BOTH OF AUCKLAND, NEW ZEALAND.

CASEMENT STAY.

Application filed October 21, 1922. Serial No. 595,992.

To all whom it may concern:

Be it known that I, LESLIE HALWORTH CLARK, a subject of the King of Great Britain, residing at Kohimarama, Auckland, New Zealand, have invented a new and useful Improved Casement Stay, of which the following is a specification.

My invention relates to the ordinary type of window casement stay in which a stay bar is employed and hinged to the window casement and is combined with a locking pin that is fixed to the window frame so that it may be locked to such pin at any point along its length. The invention relates more particularly to that class of stay in which the bar is formed with apertures in it at intervals, each of which is adapted to pass over the locking pin on the window frame.

Hitherto these stay bars have generally been formed in one rigid length, so that when the casement is partially, or fully, closed, the bar projects inwards into the room and forms an obstruction against the proper hanging of curtains or window blinds. The object of my invention is to provide a construction of bar that, when drawn in either partially or wholly, may be allowed to hang vertically down against the wall beneath the window frame and thus be free from the possibility of obstructing the blinds or curtains in the manner referred to.

The invention therefore consists in constructing the bar with a hinge attachment to the bracket by which it is fixed to the sash, such hinge being of a nature such as to form a universal joint to allow of the bar bending or hanging from any angle, combined with the construction of the bar of two lengths arranged end to end to form the whole bar, and preferably each formed by about half the length of the full bar. These two lengths are hinged together in such a manner that the inner end is capable of turning down on the outer end, and the hinge is so constructed that when the two lengths are turned into a continuous plane, they may be locked together to form a rigid stay to be used when the casement is opened to half, or more than half, its intent.

This construction is illustrated in the accompanying drawings, in which:

Figure 1 is a side elevation of the stay,

Figure 2 is a plan thereof, and

Figure 3 a longitudinal sectional elevation

through the hinge connecting the two parts of the stay together.

In carrying out the invention, the stay is made up of two lengths A and B joined end to end and the outer of which lengths, A, has its outer end connected to the bracket plate C by means of which the stay is attached to the casement sash frame in the usual way, by the universal joint D. This joint is so designed as to permit of the stay swinging down vertically for its full length when the sash is closed, and also to provide for the stay assuming the varying angles horizontally that are required when staying the sash in its more or less opened positions.

The hinge joint by means of which the two lengths A and B are connected together is made by forming the length A with a medial slot E extending longitudinally from its extremity and by forming the adjacent end of the length B with a tongue F projecting longitudinally therefrom, that fits neatly into the slot E. A pivot pin G is then passed through the overlapped joint thus formed so that the length B may turn up and down in the vertical plane. The tongue F lies wholly within the slot E when the length B is positioned straight with the length A.

The two lengths are designed to be locked rigidly in the same plane by making the pin G to slide longitudinally through the joint and in forming it with a second leg G' that is designed to be pushed into apertures H formed respectively in the tongue and slot sides at a distance from the pivot point. These apertures H come into coincidence when the length B is straightened so that the leg G' may then be pushed into them, thereby forming with the pin G, a lock to keep the length B from turning. The pin G is made long enough to permit of the leg G' being drawn out of these apertures when it is required to turn the length B down, and to limit this sliding movement and prevent the complete withdrawal of the pivot, the back end thereof is made with a head g as shown in Figure 2.

This joint may be rendered still more rigid by forming the tongue F with an extension F' beyond its end and of a depth of about half the depth of the tongue and by forming the top of the length A with a groove E' extending in from the end of the slot, into which groove the extension F' will enter when the length B is straightened out.

It will be readily understood that when the sash on which the stay is fitted is being retained open at half, or less, of its opening range, the length A will be carrying the strain, so that the length B may then be turned vertically down to lie neatly against the wall beneath the casement frame, by merely drawing out the pin G and allowing the length B to drop. When the sash is to be stayed at more than half open, the length B is turned up and made rigid with the length A in the manner described.

I claim:—

1. A casement stay comprising two sections movable relative to each other, a movable pivot pin pivotally connecting the said sections at their inner ends and provided with a bent portion adapted to engage registering apertures in the said sections for locking the same in position when aligned.

2. A casement stay comprising two relatively movable sections, one having a slot

at its inner end, a tongue at the inner end of the other section adapted to fit into said slot, and a movable pivot pin pivotally connecting the said sections at their inner ends passing through registering apertures in said sections and having a bent portion adapted to pass through a second set of registering apertures when the said sections are in alignment, thereby locking said sections in position.

3. A casement stay as specified in claim 2, in which the said tongue is provided with an extension adapted to enter a groove extending from the end of the slot in the other section.

In testimony whereof, I affix my signature.

LESLIE HALWORTH CLARK.
